UNITED STATES PATENT OFFICE.

HARRY PEARSE AND EYRE FRANCIS IEVERS, OF BUENOS AIRES, ARGENTINA, ASSIGNORS TO THE FRANCIS EYRE COMPANY, OF NEW YORK, N. Y.

MULTIPLE-EXPANSION ROTARY ENGINE.

SPECIFICATION forming part of Letters Patent No. 718,725, dated January 20, 1903.

Application filed August 21, 1901. Serial No. 72,806. (No model.)

To all whom it may concern:

Be it known that we, HARRY PEARSE and EYRE FRANCIS IEVERS, citizens of Argentina, residing at Las Barrancas, Campana, Buenos Aires, Argentina, have invented new and useful Improvements in Multiple-Expansion Rotary Engines, (in respect whereof we have caused applications for patents to be made in Great Britain, to bear date April 4, 1901, No. 7,191; in France, to bear date April 13, 1901, No. 298,397, and in Germany, to bear date April 12, 1901,) of which the following is a specification.

This invention relates to multiple-expansion rotary engines of the type wherein two sets of rotators or "pillows" are mounted upon shafts arranged parallel to each other in a casing in such a manner that the pillows upon the one shaft enter the rotary path of the aligned pillows pertaining to the other shaft and are exposed to steam or other fluid pressure whereby their rotation in opposite directions is effected, the objects of the present improvements being to simplify the construction of such engines and to secure a higher degree of efficiency.

A rotary engine of the type referred to and embodying the present improvements is illustrated in the accompanying drawings, whereof—

Figure 1 is a view, partly in longitudinal section on the line xx in Fig. 2 and partly in elevation, Fig. 2 being an end elevation, and Fig. 3 a plan view, part of the upper half of the casing being removed to show the internal arrangement and one of the bearing-chambers being in horizontal section. Fig. 4 is a detached view of the two sets of pillows and their respective shafts, Fig. 5 being a corresponding end view. Figs. 6 and 7 are respectively a face view and a side view of the means employed for coupling the pillow-shafts. Fig. 8 is a view, drawn to a larger scale, partly in section and partly in elevation, and Fig. 9 a similar view at right angles thereto, showing the construction of the pillows, whereby their working surfaces are rendered steam-tight. Figs. 10 and 11 are transverse sections taken on the lines yy and zz , respectively, in Fig. 1. Fig. 12 is a transverse section illustrating

the application of a D-valve for use in reversing the engine. Figs. 13 and 14 are respectively a longitudinal and a horizontal section of a modified form of engine.

55

For the purpose of the present description it is assumed that the engine has four sets of pillows arranged, respectively, in four chambers or cylinders, the steam or other motive fluid being exhausted from the first or high-pressure cylinder into the second, from thence into the third, and so into the fourth or low-pressure cylinder.

According to the construction illustrated in Figs. 1 to 11, inclusive, the engine comprises a bipart casing A, bolted together, as shown at a , and provided with end plates or covers A' A², the joints between the parts of the casing being rendered steam-tight by any suitable means. In transverse section the form of the casing approximates that which would result from uniting two parallel hollow cylinders. The interior of the casing is furnished with transverse partitions $b b c c$, the casing thus comprising end chambers $d d$, 75 and intermediate chambers or cylinders $e' e^2$, $e^3 e^4$. Within the latter chambers and fast upon shafts F' F² are mounted two sets of pillows $f' f'$, $f^2 f^2$, $f^3 f^3$, $f^4 f^4$, so arranged upon the respective shafts that each set cooperates with the adjoining set. The shafts F' F² are carried in bearings housed in casings $a' a'$, formed on the respective end plates A' A². One of the shafts F' constitutes the driving-shaft and extends outward through a stuffing-box a^2 at one end of the casing A and is provided with a driving-pulley f or other means for transmitting power. A plumber-block bearing f^5 supports the outer extremity of the driving-shaft, while 80 the opposite end thereof, as also the ends of the shaft F², terminate within the casings $a' a'$. Each pillow $f' f^2 f^3 f^4$ is preferably constructed as shown in Figs. 8 and 9, a ring or strip g being inserted in a recess formed 85 for its reception upon each face, the said strips securing the pillow steam-tight between the transverse partitions by means of springs g' . The diametrically opposite extremities of each pillow are furnished each with a packing G, whereby steam-tight contact is made 90 with the inner surface of the casing A and

100

with the coöperating pillow. Each packing G may be formed of two strips g^2 g^3 , fitted in a dovetail or undercut recess g^3 in such a manner as to be capable of radial movement 5 in relation to the shaft F' or F^2 . A bar g^4 of triangular form in transverse section enters between the strips and serves to force the latter outward by means of springs g^5 .

Instead of the packing G being arranged 10 in the manner shown the object may be accomplished by means of a fixed packing-strip or of a packing of any other desired construction.

The ends of the shaft F^2 rotate in bearings 15 h h' , arranged in the chambers a' , and whereof the effective pressure may be adjusted by means of springs h' h' and set-screws h^2 h^2 . The object of these adjustable bearings is to insure steam-tight rolling contact between 20 the contiguous pillows on the respective shafts F' F^2 and to equalize wear.

Each of the pillows $f' f^2 f^3 f^4$ is arranged on its shaft F' or F^2 in such a manner that its longer diameter is at an angle of ninety degrees to that of the immediately preceding or 25 succeeding pillow on the same shaft.

On each of the shafts F' F^2 are arranged two sets of disks $i' i^2 i^3$ and $i^4 i^5 i^6$, adapted to rotate in the before-mentioned end chambers d d , the former set on the one shaft gearing with the latter set pertaining to the other shaft. The disks i^3 and i^6 of each respective set are of circular formation and mounted concentrically upon the shaft F' or 35 F^2 , the diameter of each disk being equal to the distance between the axes of the shafts F' F^2 , so that they remain in constant rolling contact with each other and maintain the shafts F' F^2 at the correct distance apart. The 40 disks $i' i^2 i^4 i^5$ have the same peripheral shape as the pillows $f' f^2 f^3 f^4$ and are preferably arranged with their longer diameters at angles of thirty degrees and sixty degrees in relation to the corresponding diameters of 45 the pillows, with the effect that they do not coincide with each other or with the pillows. These disks i' , i^2 , i^3 , i^4 , i^5 , and i^6 , like the pillows $f' f^2$, rotate in contact with each other and serve to couple the shafts F' F^2 after the 50 manner of ordinary spur-gearing, but with considerably less friction.

The several partitions b and c are divided like the casing A , the latter being provided with recesses for their reception, and each partition is adapted for the passage and rotation of the shafts F' F^2 . The partitions c c are provided with passages $c' c^2 c^3$, which establish communication between the exhaust-port c^4 , c^5 , or c^6 of the one cylinder and the admission-port c^7 , c^8 , or c^9 of the next succeeding cylinder.

Upon opening a valve J steam or other motive fluid is admitted into the chamber or cylinder e' through the port j , and operates to 65 rotate the pillows $f' f^2$ therein in opposite directions, as indicated by the arrows. When the pillows f' have turned through one hun-

dred and eighty degrees, the steam leaves the chamber e' by way of the port c^4 , and passing through the passage c' , gains access to the 70 port c^7 and from thence to the chamber or cylinder e^2 . This latter chamber is longer than the chamber e' , so that the steam is subject to an expansive action therein during a quarter of a revolution and is deprived of 75 some of its initial pressure. After operating the pillows $f^2 f^2$ this fluid leaves the cylinder e^2 by way of the port c^5 and passage c^2 and enters the chamber e^3 by way of the port c^8 , further expansion taking place in this latter 80 chamber. By way of the exhaust-port c^6 , passage c^3 , and inlet-port c^9 , the steam now enters the cylinder e^4 , wherein it is still further expanded and from whence, after operating the pillows $f^4 f^4$, it escapes through the exhaust j' into the atmosphere, or it may be conducted to a condenser, as desired.

When starting, especially if the engine be under load, it may be expedient to admit the high-pressure steam to one or other, or both, of 90 the chambers e^3 e^4 . For this purpose these latter chambers are in communication with the steam-supply by means of pipes k , these pipes being fitted with non-return valves, such as k' . This auxiliary steam-supply is 95 shut off immediately the engine has commenced to revolve, and in order to prevent the steam so admitted gaining access to the under side of the pillows $f^2 f^3$ the passages c^2 c^3 are provided with valves l , which operate 100 automatically to admit the auxiliary steam-supply and to allow of the working of the engine under ordinary conditions.

The engine is provided with an expansion-valve m of the double-balanced type, which 105 is opened and closed four times at each rotation of the driving-shaft F' . The valve-rod is pivoted to one end of a lever m' , formed with a quadrantal slot m^8 , wherein works a stud m^2 , carried by the link m^3 . This link 110 m^3 is pivoted to a spring-controlled lever m^4 . A rocking shaft m^5 , connected with the lever m^4 , is operated by the arm m^6 and double cam m^7 , the latter being secured to the driving-shaft F' . At about midway of its length the 115 link m^3 is connected with one end of a link m^9 , whereof the other end is pivoted to a bell-crank lever m^{10} in connection with the governor M . When the speed of the engine varies, the governor M causes the stud m^2 , pertaining to the link m^3 , to move nearer to or farther from the pivot m^{11} of the lever m' , with the effect that the degree of opening of the valve m is varied.

Instead of employing spring-pressed packings g , as above described, on the several pillows the steam may itself be employed to provide or assist in providing the necessary steam-tight contact between the pillows and the partitions b and c . According to one mode of 130 carrying out this method of working (illustrated in Figs. 13 and 14) the partitions are arranged so as to be capable of lateral expansion. Each partition is formed as two plates

or disks c^{10} c^{11} , held apart by interposed springs c^{12} . One of the plates c^{10} or c^{11} of each partition has a small port c^{13} for the admission of steam between the plates, the pressure of the steam forcing the plates outward, so that their exterior surfaces make steam-tight contact with the contiguous faces of the pillows. The outer plates pertaining to the partitions b may fit in annular recesses in the wall of the casing A . The modification of the passages c' , c^2 , and c^3 rendered necessary by the use of partitions with lateral expanding sides will be clearly understood upon reference to the drawings, Figs. 13 and 14, and do not require any detailed description.

In the operation of the engine, the pillows $f' f'$ being arranged at ninety degrees to the pillows $f^2 f^2$, it follows that when the steam is exhausted from the chamber e' it enters the chamber e^2 at the moment when the smallest space between the pillows $f^2 f^2$ is presented for its occupation. During a quarter of a revolution of the pillows this space gradually increases, with the result that the full effect of the steam-pressure is obtained. As the pillows uncover the outlets $c^4 c^5 c^6$ of their respective chambers at the completion of each quarter of a revolution the steam is exhausted from the largest space in that chamber into the smallest space of the succeeding chamber, the increased length of the succeeding pillows compensating for the nominal decrease in pressure incidental to the expansion of the steam.

Although the foregoing description refers to an engine of the non-reversing type, it will be apparent that by providing the engine with D-valves, such as shown at n , Fig. 12, it may be rendered reversible.

o is the exhaust-port.

What we claim as our invention, and desire to secure by Letters Patent, is—

1. A rotary engine comprising a casing, two

parallel shafts, and coöperating pillows thereon to be acted upon by the motive agent, and 45 hollow walls dividing said casing into separate chambers, one for each set of pillows, said partitions having ports and channels for conducting the motive agent from one chamber to another, substantially as set forth. 50

2. In a rotary engine, a casing A having chambers for the reception of pillows of various dimensions, shafts F' and F^2 , disks i', i^2 , i^3 , i^4 , i^5 , i^6 keyed upon respective shafts, as shown; the disks pertaining to the one shaft 55 working correlativey and in contact with those pertaining to the other shaft, substantially as and for the purposes specified.

3. A rotary engine comprising a bipart casing formed with several chambers each furnished with pillows and having a dividing-wall adapted for conducting the motive agent, and having the herein-described means for use in starting the engine, same comprising a non-return valve in communication with 65 the supply-pipe for the motive agent and a valve arranged in the dividing-wall, substantially as specified.

4. The combination, with a rotary engine comprising a bipart casing formed with several chambers, each furnished with a set of pillows arranged between dividing-walls formed with passages and ports for conducting the motive agent, of an expansion-valve, means for operating said valve uniformly, a 70 governor, means for operating the latter, and intermediate means whereby the governor controls the said expansion-valve.

In testimony whereof we have signed our names to this specification in the presence of 80 two subscribing witnesses.

HARRY PEARSE.
EYRE FRANCIS IEVERS.
